METHOD AND APPARATUS FOR ADDING
YARN ENDSRalph C. Pollman, Seaford, Del., assignor to E. I.
du Pont de Nemours and Company, Wilming-
ton, Del., a corporation of Delaware

Application June 2, 1952, Serial No. 291,099

4 Claims. (Cl. 28—71.5)

1

This invention relates to an apparatus for combining running ends of yarn to form a tow or rope of yarn, and is more particularly concerned with an apparatus for adding an end of yarn to moving yarns without interrupting the movement of the yarn.

In the production of staple fiber, yarns from several creel or spinning positions may be combined into a large bundle called a tow or rope. The tow is frequently a more convenient form in which to handle the fibers during aftertreatment, including that of cutting into short lengths called staple. The addition of an end of yarn to moving yarn or tow is relatively easy when the yarns are wet, as the water causes the yarns to adhere. Dry hydrophilic yarns, such as acetate rayon yarns, can be combined by sponging in, i. e., the yarns are wetted to cause them to adhere. However, certain of the new synthetic fibers do not wet easily and it is difficult to add a yarn end to running yarn or tow without interrupting movement of the yarn.

Accordingly, it is an object of the present invention to provide an apparatus which is effective and convenient for adding a yarn end to running yarn or tow, regardless of the condition and type of yarn, and without interrupting movement of the running yarn or tow. Other objects of the invention will become apparent from the following description, the accompanying drawing and the claims.

In accordance with the present invention, a mechanical false twister is used to wind a yarn end about a running yarn or tow and guide the added end against a cutter to trim off the free end. The false twister preferably produces a twist by means of a plurality of skew elements which are mounted to be swung into engagement with the running yarn or tow. With these elements in the disengaged position, the yarn or tow and the end to be added are guided between the elements without twist being imparted. The elements are then swung into position to engage the running yarn at successive positions and cause it to rotate. The free end is held and, therefore, is wound about the running yarn. The surplus end is then cut off next to the yarn or tow by a suitable cutter.

In the drawings, which illustrate a preferred embodiment of the invention,

Figure 1 is a plan view of an apparatus in accordance with the invention, with the twist-producing elements in the disengaged position,

Figure 2 is a corresponding plan view with the elements swung into operating position,

2

Figure 3 is a front elevation of the apparatus shown in Figure 2, and

Figure 4 is an elevation of one of the false twister elements.

5 Referring now to Figure 1, it is seen that the apparatus is so positioned that a tow or rope 10 of yarn can proceed in an unobstructed straight line along the line A—A when the apparatus is in this disengaged position. False twister elements 11 and 12, together with the cutting device 13, are rigidly affixed to movable plate 15 which pivots at bearing 16 near the center of base plate 17. Handle 18, likewise rigidly connected to plate 15, is used to move the apparatus into and out of the engaged position. False twister element 19 is movably mounted on baseplate 17, being rigidly attached to shaft 20 which pivots in bearing 21 and is rigidly connected to crank arm 22. In turn plate 15 is rigidly connected to crank arm 23 through shaft 24 passing through bearing 16. These two crank arms are interconnected through arm 26 so that movement of plate 15 by handle 18 moves twister element 19 through an equal angle in the opposite direction.

10 25 To operate the apparatus, a yarn end 30 which is to be tied into the moving tow is brought along line A—A of Figure 1 to the middle false twister element 12, passed around this element, and then is pulled continuously back in the direction from which it came by suitable means, as with an aspirating device. Other means such as winding on a waste spool or even hand-over-hand pulling can be used to keep the yarn end reasonably taut and traveling at a speed comparable to that of the tow 10.

30 35 The handle 18 is now swung through 90° to the position shown in Figure 2. This turns the false twisting elements into position to engage the tow. The yarn end and the tow now pass together in contact with false twisters 11 and 12, and the tow continues by itself to contact false twister 19 and pass on to the next operation. The yarn end 30 leaves the tow after passage through false twister 12 and is pulled away in front of cutting device 13. The free false twisters are all arranged to twist the tow in the same direction; as illustrated they will cause the tow to rotate in a counter-clockwise direction when looking in the direction of tow travel. Since the

40 45 end of yarn is held, it will be wound around the rotating tow and secured in place. Immediately thereafter the travelling tow will pull the yarn end against the cutting device 13 and surplus yarn will be trimmed off close to the tow. The 50 55 added yarn end will then travel along with the

tow. The false twisting elements are now disengaged from the tow by throwing handle 18 back to the original position of Figure 1. Additional yarn ends may be added by repeating the above operation.

The cutting device 13 is indicated in the drawings as an electric hair clipper. Preferably this is a clipper of the animal haircutting type. However, a variety of cutting devices can obviously be used. A simple cutting edge, such as a razor blade, will sometimes serve for the purpose.

The false twisting elements can be of various types. Those shown in the drawings utilize the principle that a yarn drawn at an oblique angle over a guide will be caused to twist. A point on the yarn surface contacting the guide surface will be pushed to one side in a direction which tends to cause the point to move parallel to the guide surface. Since this force is not balanced by the effect of a contacting surface on the other side of the yarn, an unbalanced torque is produced which twists the yarn.

As shown in Figure 3, the tow 10 moves horizontally from right to left in front of guiding surface 31 of false twister 11. This surface 31 is slanted upward to the left at an angle of about 30° to the horizontal. Hence the far side of the tow, where it contacts this surface, is moved upward and the tow is twisted in a counter-clockwise direction when viewed with the tow travelling away from the observer as shown in Figure 4. The tow next passes horizontally behind the guiding surface 32 of the second false twister 12, and this surface is slanted upward to the right at an angle of about 30° to the horizontal. Hence the near side of the tow, where it contacts this surface, is moved downward and the tow is again twisted in a counter-clockwise direction. The last false-twisting element 19 is similar to and engages the tow in the same manner as the first element 11. The tow, passing in front of the oblique guiding surface 33 is again twisted in a counter-clockwise direction. The effect of these three false-twisters acting to apply twist in the same direction is to impart an S-twist to the tow approaching the apparatus, and an equal and opposite Z-twist to the tow leaving the apparatus, as indicated in Figure 3.

Figure 4 shows a few more details of the type of false-twisting element used in this preferred embodiment. Triangular projections 35 and 36 serve to direct the tow into position on the oblique guiding surface 31. The portions of these surfaces which contact the tow are made round and smooth to avoid damaging the tow fibers. The false-twister is provided with a right-angle flange at the bottom for mounting the element on plate 15.

Although the description of the operation of the device has dealt with the tying-in of a free end of yarn into a running end of tow, the invention is equally applicable to the tying-in of a plurality of free ends of yarn into a running end of tow. Usually the tow will comprise a large

5 number of ends of yarn, e. g., from 40 to 50, up to several hundred, with the result that the total denier of the tow may vary between rather wide limits, i. e., from 2 to 3 thousand, up to 2 to 3 million or even more.

While the invention has been described in terms of a preferred embodiment thereof, it is apparent that many different embodiments may be made without departing from the spirit or the scope of the invention and it is to be understood that the invention is not limited by the specific illustrations except to the extent defined in the following claims.

What is claimed is:

1. A method for adding a yarn end to running yarn which comprises guiding running yarn and a yarn end together to form a tow and then guiding the free end of yarn away from the running yarn, rotating the tow so that the yarn end is wrapped around the running yarn, and immediately thereafter cutting off the free end of added yarn close to the tow.

2. An apparatus for adding a yarn end to running yarn including in combination a mechanical false-twister adapted to bring running yarn and a yarn end together to form a tow and then rotate the tow, means for guiding the free end of yarn away from the tow at said false twister so that rotation of the tow will wrap the yarn end about the tow, and cutting means located adjacent to said false twister in position to cut off the free end of yarn as soon as the yarn end is wrapped about the tow.

3. An apparatus for adding a yarn end to running yarn including in combination a false twister comprising a plurality of skew elements arranged to engage running yarn at successive positions and cause the yarn to rotate, means for guiding a free end of yarn away from the running yarn at a point between two of said skew elements, and cutting means located adjacent to said guiding means in position to cut off the free end of yarn close to the running yarn.

4. An apparatus for adding a yarn end to running yarn including in combination a plurality of skew elements mounted to be swung into engagement with running yarn, said elements being arranged to contact the running yarn at oblique angles at successive positions and cause the yarn to rotate in the same direction, means for guiding a free end of yarn away from the running yarn at a point between two of said skew elements, and an automatic clipper adapted to cut off the free end of yarn close to the running yarn between said guiding means and the immediately subsequent skew element.
